J. G. WEIR

BOILER FEEDING APPARATUS

Filed March 10, 1924

Patented Nov. 17, 1925.

1,561,675

UNITED STATES PATENT OFFICE.

JAMES GEORGE WEIR, OF CATHCART, GLASGOW, SCOTLAND, ASSIGNOR TO G. & J. WEIR, LIMITED, OF CATHCART, GLASGOW, SCOTLAND.

BOILER-FEEDING APPARATUS.

Application filed March 10, 1924. Serial No. 698,326.

To all whom it may concern:

Be it known that I, JAMES GEORGE WEIR, a subject of the King of Great Britain, and residing at Cathcart, Glasgow, Scotland, have invented certain new and useful Improvements in Boiler-Feeding Apparatus; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

Electrically-driven centrifugal boiler feed pumps as commonly used are unsatisfactory owing to the practically constant speed of the driving motor. This results in a wide variation of feed pressure at the boiler between full load and light load conditions. The feed pressure is also incapable of easy adjustment to suit the variation in conditions which generally occurs when the plant is running. On the other hand electrically-driven feed pumps are convenient and are in general more economical in power cost than steam pumps.

The present invention consists in a combination of apparatus for boiler feeding purposes. The invention will be described in the following specification and defined in the annexed claims.

In the drawings:—

Figure 1 illustrates diagrammatically the carrying of the invention into effect, in one convenient manner; and,

Figure 2 is a detail view of a modification thereof.

a is a variable-speed pump driven by a steam turbine *b*. This pump is arranged in series with a constant-speed pump *c* to which it discharges by the pipe *r*. The pump *c* is driven by an electric motor *d*. This electrically-driven pump is arranged to produce under no-load conditions a pressure difference between its suction and discharge of somewhat less than the full boiler pressure. The steam-driven pump, which is placed between the feed water supply *e* and the electrically driven pump, has its steam supply— which is conveyed to it by the pipe *t*—controlled by a pressure-operated valve *f*. This valve is connected up by the pipe *h* with the pipe *m* through which the electrically driven pump delivers into the boiler feed pipe *n*.

The valve is actuated by the pressure of discharge of the electrically-driven pump and is so loaded that steam is supplied to the steam pump whenever the discharge pressure of the electrically-driven pump falls below a given value. The steam pump then starts (or accelerates) and imposes sufficient pressure on the suction of the electrically-driven pump to raise the discharge pressure of the latter to the desired value. Thus the steam pump acts in such a manner that it augments the pressure generated by the electrically-driven pump to the pressure desired in the feed pipe. This pressure may be constant or variable. The work which the steam pump will be called upon to do will therefore depend inter alia on the frictional resistance in the feed pipe and on the characteristics of the electrically-driven pump under varying loads.

The pipe *h* might be connected up to the feed pipe *n* instead of to the pipe *m*.

The individual advantages appertaining to the two types of pump are thus conserved in the combination.

A further and important advantage of this combination lies in the fact that the steam-driven pump may be arranged to act as a water-extraction pump, i. e. to draw the feed water directly from the condenser. In this case *e* represents the condenser (diagrammatically). Such an employment of the pump *a* enables the feed circuit to be arranged as a closed system.

A further advantage lies in the fact that a steam-driven pump may be inserted in existing installations where an electrically-driven feed pump (or pumps) is already installed.

A steam-driven pump may be employed as hereinbefore described in the feed circuit where a plurality of electrically-driven constant speed pumps are used in parallel.

When the variable-speed pump is employed (as above mentioned) as a water-extraction pump and when it is controlled by action on its steam supply valve, e. g. the valve *f* in the figures, a by-pass *S* as shown in Figure 2 may be provided to this valve so that, even when the pressure in the feed pipe into which the constant-speed pump delivers is the maximum or the full amount desired, sufficient steam is supplied to the water-extraction pump to permit it to withdraw water from the condenser and dis-

charge it at a pressure slightly in excess of atmospheric pressure.

In all cases in this specification where the expression "constant-speed" has been used, 5 it is to be understood that the speed is not necessarily absolutely constant but is approximately or practically constant.

Having thus described my invention, what I claim as new and desire to secure by Letters Patent is:—

1. The combination with a feed pipe for boilers of a constant-speed pump, a variable-speed pump arranged in series with, and on the suction side of, the said constant-speed pump and co-acting with it to deliver feed water into the said feed pipe, and means whereby the said variable-speed pump is controlled by the pressure in the said feed pipe.
2. The combination with a feed pipe for boilers of a constant-speed pump, a variable-speed pump arranged in series with, and on the suction side of, the said constant-speed pump and co-acting with it to deliver feed water into the said feed pipe, a steam engine which drives the said variable-speed pump, and means whereby the said variable-speed pump is controlled by the pressure in the said feed pipe.
3. The combination with a feed pipe for

boilers of a constant-speed pump, a condenser, a variable-speed pump arranged in series with, and on the suction side of, the said constant-speed pump, and arranged to withdraw water from the said condenser, 35 and arranged to co-act with the said constant-speed pump to deliver feed water into the said feed pipe, a steam engine which drives the said variable-speed pump, means whereby the said variable-speed pump is 40 controlled by the pressure in the said feed pipe, and means whereby sufficient steam is always supplied to the said steam engine to permit it to withdraw water from the said condenser and discharge it at a pressure 45 slightly in excess of atmospheric pressure.

4. The combination with a feed pipe for boilers of a constant-speed pump, a direct-current electric motor which drives the said pump, a variable-speed pump arranged in 50 series with, and on the suction side of, the said constant-speed pump and co-acting with it to deliver feed water into the said feed pipe, and means whereby the said variable-speed pump is controlled by the 55 pressure in the said feed pipe.

I hereby sign my name to this specification.

JAMES GEORGE WEIR.
